UNITED STATES PATENT OFFICE.

ALBERT WISNER, OF WARWICK, NEW YORK, ASSIGNOR TO ELIZABETH C. SEAMAN, OF NEW YORK, N. Y.

DESIGN FOR A COOLING-DRUM FOR MILK-COOLER AERATORS.

SPECIFICATION forming part of Design No. 35,531, dated December 31, 1901.

Application filed October 7, 1901. Serial No. 77,917. Term of patent 14 years.

To all whom it may concern:

Be it known that I, ALBERT WISNER, a citizen of the United States, residing at Warwick, Orange county, New York, have invented and produced a new, useful, and original Design for a Cooling-Drum for Milk-Cooler Aerators, of which the following is a specification.

The leading feature of my design is a drum for milk-cooler aerators whose cooling-surface is undulated by undulations running at an angle to the vertical axis of the drum and having a rim or flange extending downwardly and outwardly from the lower edge of the drum at a greater angle to the vertical axis than the angle made by the sides of the drum with such vertical axis, which downwardly depending flange is surrounded by an upwardly-projecting rim.

In the accompanying drawings I have shown a drum for a milk-cooler aerator presenting an embodiment of my design.

In the drawings, Figure 1 is a side elevation, partly in section, of the drum. Fig. 2 is a plan view thereof.

In the drawings, *a* indicates a drum of general frusto-conical form, having undulations *b* running laterally to the axis of the frustum. Projecting downwardly and outwardly from the lower edge of the frustum is an annular *d*, which forms a greater angle with the axis of the drum than the angle formed by the walls of said drum with said axis. An upwardly-projecting annular rim *c* projects upwardly and outwardly from said flange *d*.

What I claim is—

The design for a cooling-drum of a milk-cooler aerator, substantially as herein described and shown in the drawings.

In testimony whereof I have signed my name to this specification, in the presence of two subscribing witnesses, this 25th day of September, 1901.

ALBERT WISNER.
